DESIGN.

S. F. BOYLSTON.

GEAR FOR CHILDREN'S CARRIAGES.

Patented Feb. 23, 1886.

UNITED STATES PATENT OFFICE.

SAMUEL F. BOYLSTON, OF NEWARK, NEW JERSEY.

DESIGN FOR GEAR FOR CHILDREN'S CARRIAGES.

SPECIFICATION forming part of Design No. 16,539, dated February 23, 1886.

Application filed October 24, 1885. Serial No. 180,875. Term of patent 7 years.

To all whom it may concern:

Be it known that I, SAMUEL F. BOYLSTON, a citizen of the United States, residing in the city of Newark, county of Essex, State of New Jersey, have invented and produced a new and original Design for Springs and Gear for Use in Perambulators for Children, of which the following is a specification, reference being had to the accompanying drawing, forming part thereof.

As shown in the drawing, the leading feature of my design is the shape of the gear, produced by reason of the curved handle S passing into the straight reach X, the latter having superposed the curved bow A A, with the intermediate upwardly - curved bow, B, the

rear bow A being placed at the junction of the straight reach X with the curved handle S.

What I claim as my invention, and desire to secure by Letters Patent, is—

The design for the gear of children's carriages herein shown and described, the same consisting of the curved handle S passing into the long reach X, the latter having superposed the curved bows A A, with the intermediate upwardly - curved bow, B, the rear bow A being placed at the junction of the straight reach X with the curved handle S.

SAMUEL F. BOYLSTON.
